CENTRIFUGAL SPINNING BUCKET

Henry J. McDermott, Prospect Park, and Richard W. Stanley, Drexel Hill, Pa., assignors to American Viscose Corporation, Wilmington, Del., a corporation of Delaware

Application February 27, 1942, Serial No. 432,708

20 Claims. (Cl. 57—76)

This invention relates to improvements in centrifugal spinning buckets, and particularly to means for removing the cakes of wound filamentary material therefrom.

It is an object of the invention to provide a means for facilitating the removal of cakes from spinning buckets and to facilitate their handling and transportation while protecting them from damage. An additional object is to provide a novel cover locking means for spinning buckets which are automatically released upon application of the cake-removing means. Further objects of the invention will be apparent from the drawings and description thereof.

In the drawings illustrative of the invention, Figure 1 shows the device of the invention in position for removing a cake from a spinning bucket.

Figure 2 shows a releasing device for the device of Figure 1.

Figure 3 shows a modified form of cake-removing device.

Figure 4 shows the combination of the device of Figure 1 with a modified form of cover.

Figure 5 is a plan view of the modified form of cover of Figure 3, and

Figure 6 is another modification of the cover.

As shown in Figure 1, the spinning box 2 is provided with a removable bottom 3 and a cover 4. The spinning bucket is also provided with a spindle bearing 5 and the funnel guide centering button or plug 6. During the formation of the cake 7 between the removable bottom 3 and the cover 4, the cover is held in place by a suitable ring of rubber or other flexible material adapted to fit in the groove 8 provided in the upper internal periphery of the spinning bucket for that purpose.

After the winding of the cake 7 in the bucket, the rubber ring is removed from the groove 8 and the cake is ready to be removed together with the removable bottom and cover by the device constituting this invention. The cake-removing means is constituted of the cylindrical tube 9 fastened at its upper end to the flared member 10 across whose diameter the handle 11 extends. This handle 11 may be a solid rod or hollow tube as shown. The other extremity of the tube 9 is flared inwardly as at 12 and this inwardly flaring portion is provided with slots 13 adapted to accommodate the spring member 14. This spring member has a central portion 15 in the form of an inverted U and intermediate hook-like portions 16 from which relatively straight portions

17 extend along the inner face of the tube 9 within which they are fastened by suitable rivets. The inner periphery of the removable bottom 3 slopes downwardly and inwardly in order to cooperate with the flared portion 12 of the cake-removing means so that the lower end of the cake-removing means seats itself firmly upon the removable bottom 3. This removable bottom is formed with an undercut portion to accommodate 10 the hooks so that when the cake-removing means is inserted to its full extent within the spinning bucket, the spring hooks engage beneath the removable bottom 3 and clamp it firmly in position against the seat provided on the cake-removing means. This firm engagement of the removable bottom with the cylindrical tube has the advantage that it prevents distortion of the cake during handling that otherwise would occur because of sudden jolts, jerks and any swinging movements. 15 The outside diameter of the tube 9 of the cake-removing means is preferably made for a sliding fit within the inside periphery of the cover 4 so that the cover acts as a guide for the tube. The cake removing means therefore cannot be inserted in a manner which would cause damage to 20 the inside of the cake 7. The cake-removing means is easily inserted manually by grasping the handle 11. It is surely guided into seating engagement with the bottom 3 without risk of damage to the interior of the cake 7, and upon removal of the cake with cover and bottom, there is obtained a cake package which is readily transportable as such to the next location of operation upon the cake. This 25 transportation may be to any point of operation, particularly to a conveyor or to a machine for wrapping the cake. Whatever the point of destination of the cake package, the operating machine at that point may be provided with a suitable releasing means, such as shown in Figure 2. For example, a belt or chain conveyor may be provided with the releasing platform designated by the reference character 18 in Figure 2. One such platform is provided at each point on the conveyor or other machine intended to receive a cake 30 and it may be formed integrally with the conveyor or the like or it may be attached thereto or otherwise supported thereon. The platform consists of an upper annular surface 19 surrounding 35 a depression 20 whose diameter corresponds to the smallest diameter of the inside periphery of the removable bottom 3 and is sufficiently deep to receive the portions of the cake-removing means extending below the removable bottom 3. As 40 shown in Figure 2, the annular surface 19 adjoins 45 the side of the removable bottom 3. The side of the removable bottom 3 is provided with a flared 50 portion 21 which is adapted to receive the flared portion 12 of the cake-removing means. The side of the removable bottom 3 is also provided with a flared portion 22 which is adapted to receive the flared portion 12 of the cake-removing means. The side of the removable bottom 3 is also provided with a flared portion 23 which is adapted to receive the flared portion 12 of the cake-removing means. The side of the removable bottom 3 is also provided with a flared portion 24 which is adapted to receive the flared portion 12 of the cake-removing means. The side of the removable bottom 3 is also provided with a flared portion 25 which is adapted to receive the flared portion 12 of the cake-removing means. The side of the removable bottom 3 is also provided with a flared portion 26 which is adapted to receive the flared portion 12 of the cake-removing means. The side of the removable bottom 3 is also provided with a flared portion 27 which is adapted to receive the flared portion 12 of the cake-removing means. The side of the removable bottom 3 is also provided with a flared portion 28 which is adapted to receive the flared portion 12 of the cake-removing means. The side of the removable bottom 3 is also provided with a flared portion 29 which is adapted to receive the flared portion 12 of the cake-removing means. The side of the removable bottom 3 is also provided with a flared portion 30 which is adapted to receive the flared portion 12 of the cake-removing means. The side of the removable bottom 3 is also provided with a flared portion 31 which is adapted to receive the flared portion 12 of the cake-removing means. The side of the removable bottom 3 is also provided with a flared portion 32 which is adapted to receive the flared portion 12 of the cake-removing means. The side of the removable bottom 3 is also provided with a flared portion 33 which is adapted to receive the flared portion 12 of the cake-removing means. The side of the removable bottom 3 is also provided with a flared portion 34 which is adapted to receive the flared portion 12 of the cake-removing means. The side of the removable bottom 3 is also provided with a flared portion 35 which is adapted to receive the flared portion 12 of the cake-removing means. The side of the removable bottom 3 is also provided with a flared portion 36 which is adapted to receive the flared portion 12 of the cake-removing means. The side of the removable bottom 3 is also provided with a flared portion 37 which is adapted to receive the flared portion 12 of the cake-removing means. The side of the removable bottom 3 is also provided with a flared portion 38 which is adapted to receive the flared portion 12 of the cake-removing means. The side of the removable bottom 3 is also provided with a flared portion 39 which is adapted to receive the flared portion 12 of the cake-removing means. The side of the removable bottom 3 is also provided with a flared portion 40 which is adapted to receive the flared portion 12 of the cake-removing means. The side of the removable bottom 3 is also provided with a flared portion 41 which is adapted to receive the flared portion 12 of the cake-removing means. The side of the removable bottom 3 is also provided with a flared portion 42 which is adapted to receive the flared portion 12 of the cake-removing means. The side of the removable bottom 3 is also provided with a flared portion 43 which is adapted to receive the flared portion 12 of the cake-removing means. The side of the removable bottom 3 is also provided with a flared portion 44 which is adapted to receive the flared portion 12 of the cake-removing means. The side of the removable bottom 3 is also provided with a flared portion 45 which is adapted to receive the flared portion 12 of the cake-removing means. The side of the removable bottom 3 is also provided with a flared portion 46 which is adapted to receive the flared portion 12 of the cake-removing means. The side of the removable bottom 3 is also provided with a flared portion 47 which is adapted to receive the flared portion 12 of the cake-removing means. The side of the removable bottom 3 is also provided with a flared portion 48 which is adapted to receive the flared portion 12 of the cake-removing means. The side of the removable bottom 3 is also provided with a flared portion 49 which is adapted to receive the flared portion 12 of the cake-removing means. The side of the removable bottom 3 is also provided with a flared portion 50 which is adapted to receive the flared portion 12 of the cake-removing means. The side of the removable bottom 3 is also provided with a flared portion 51 which is adapted to receive the flared portion 12 of the cake-removing means. The side of the removable bottom 3 is also provided with a flared portion 52 which is adapted to receive the flared portion 12 of the cake-removing means. The side of the removable bottom 3 is also provided with a flared portion 53 which is adapted to receive the flared portion 12 of the cake-removing means. The side of the removable bottom 3 is also provided with a flared portion 54 which is adapted to receive the flared portion 12 of the cake-removing means. The side of the removable bottom 3 is also provided with a flared portion 55 which is adapted to receive the flared portion 12 of the cake-removing means.

an outer downwardly sloping surface 21 which fits within the annular foot or base formed about the removable bottom 3. However, this is not essential, it being only necessary that a depression be provided to accommodate the annular foot or base of the bottom 3. Since this foot or base may have numerous other shapes and sizes and since it may be desirable to use different removable bottoms having different shapes of bases, it is preferable not to have the platform shaped to conform too closely to the base or foot of any given removable bottom as is the case in Figure 2.

Figure 3 shows a modified form of the cake removing device in position in a spinning bucket (not shown) having a cover 4 and removable cake-supporting member 3 (these parts being shown in part). This device is similar to that of Figure 1, but the lower part of the cylindrical tube 9 is cut away at regularly spaced portions, as at 22, leaving the uncut portions therebetween in the form of resilient prongs 23 having inwardly tapered feet 24 which are provided with the grooves 25 which are adapted to make a firm seating engagement with the inner periphery of the member 3. The tube 9 may be made of a resilient metal, preferably corrosion resistant, such as stainless steel, or of resilient non-metallic materials, such as phenol-formaldehyde resins.

In Figure 3, a collar 26 of elastic material, such as rubber or synthetic rubbers or elastomers, is shown between the cover 4 of the spinning bucket and the flange of the cake-removing device. This collar is adapted to be compressed upon movement of the device into engagement with the cake-supporting member 3. The compressed collar may be applied to any form of the device and assures that the device maintains firm engagement with both the cover and the cake-supporting member by taking up any slack that would otherwise result from axial shrinkage of the cake when the device is left in place on the cake for a considerable period of time, and particularly, if any liquid treatment or drying of the cake is performed while the device is still in place on the cake.

In Figures 4 to 6, the cake-removing means is shown in combination with a spinning box having a modified type of cover-locking means. The cover 27 of Figure 4 is provided with a plurality of fingers 28 pivoted within recesses at the outer periphery thereof. The spinning bucket is provided with a groove 29 adapted to cooperate with the fingers, which by virtue of their being eccentrically weighted about their pivots 30 are thrown outwardly by centrifugal force into the position shown in Figure 5, thereby forcing a pin 31 into the position shown in which it protrudes internally of the central opening 32 in the cover. The external sloped surface of the flared end 12 of tube 9 acts as a cam to force the pin 31 against the tail 33 of the finger thereby retracting it from the groove 29 in the spinning bucket and releasing the cover. As shown in Figure 4, the external surface of the flared portion 12 of the cake-removing means is formed with a substantially constant slope to assure smooth and continuous cam action along its entire length.

A modification of the bucket-engaging fingers shown in Figure 6 may be substituted for that of Figures 4 and 5. In this case the fingers 34 are in a form of bell-crank levers and cam action causes a rotation about the pivot 35 when

75 the cake-removing device is inserted into the bucket.

While preferred embodiments of the invention have been shown, it is to be understood that changes and variations may be made without departing from the spirit or scope of the invention as defined by the appended claims.

What we claim is:

1. In combination, a spinning bucket having a removable cake-supporting element provided with a seat facing at least partially away from the bottom of the bucket, means for removing said element comprising a substantially rigid member terminating in a portion adapted to seat itself firmly upon the seat portion of said element, and means for securing said removing means to said element with the member firmly seated upon the element.
2. In combination, a spinning bucket having a removable bottom provided with a seat facing at least partially toward the mouth of the bucket, means for removing said bottom comprising a substantially rigid cylindrical member terminating in a portion adapted to seat itself firmly upon the seat portion of said bottom, and means for securing said removing means to said bottom with the member firmly seated upon the element.
3. In combination, a spinning bucket having a removable bottom and a cover having a central opening, means for removing said bottom comprising a cylindrical member having a sliding fit within said opening and terminating in a portion adapted to seat itself firmly upon a cooperating portion of said bottom, and means for securing said removing means to said bottom.
4. In combination, a spinning bucket having a removable bottom and a cover having a central opening, means for removing said bottom comprising a cylindrical member having a sliding fit within said opening and terminating in a portion adapted to seat itself firmly upon a cooperating portion of said bottom, and releasable means for securing said removing means to said bottom.
5. In combination, means for taking hold of a removable cake-supporting element, a support outside of said bucket upon which the cake is to be deposited, and means on said support for automatically releasing the removable element from said first-mentioned means upon deposit of the cake thereon.
6. In combination, means for taking hold of a removable bottom supporting a cake thereon, a support outside of said bucket upon which the cake is to be deposited, and means on said support for automatically releasing the removable bottom from said first-mentioned means upon deposit of the cake thereon.
7. In combination, means insertable into a spinning bucket for taking hold of a removable bottom supporting a cake thereon, a support outside of said bucket upon which the cake is to be deposited, and means on said support for automatically releasing the removable bottom from said first-mentioned means upon deposit of the cake thereon.
8. In combination, a spinning bucket having a removable cake-supporting element and a cover, means on said cover for holding it in place on said bucket, means for taking hold of said element, and means on the latter means for releasing said cover holding means.
9. In combination, a spinning bucket having a

removable bottom and a cover, means on said cover for holding it in place on said bucket, means for taking hold of said bottom, and means on the latter means for releasing said cover holding means.

10. In combination, a spinning bucket having a removable bottom and a cover, means on said cover for holding it in place on said bucket, means insertable into said bucket for taking hold of said bottom, and means on the latter means for releasing said cover holding means upon insertion thereof into the bucket for taking hold of said bottom.

11. In combination, a spinning bucket having a removable cake-supporting element and an annular cover, means on said cover for holding it in place on said bucket comprising at least one member movable to a retracted position and to a position extending internally of the inner periphery of said cover upon motion of the cover-holding means to bucket-engaging position, means insertable into said bucket for taking hold of said element, and an annular sloping surface on said insertable means for engaging and moving said member during insertion to release said cover-holding means.

12. In combination, a spinning bucket having a removable bottom and an annular cover, means on said cover for holding it in place on said bucket comprising at least one member movable to a retracted position and to a position extending internally of the inner periphery of said cover upon motion of the cover-holding means to bucket-engaging position, means insertable into said bucket for taking hold of said bottom, and an annular sloping surface on said insertable means for engaging and moving said member during insertion to release said cover-holding means.

13. In combination, a spinning bucket having a removable bottom and an annular cover, means on said cover for holding it in place on said bucket comprising at least one member movable to a retracted position and to a position extending internally of the inner periphery of said cover upon motion of the cover-holding means to bucket-engaging position, means insertable into said bucket for taking hold of said bottom and terminating in a portion adapted to seat itself firmly upon a cooperating portion of said bottom, and an annular sloping surface on said insertable means for engaging and moving said member during insertion to release said cover-holding means.

14. In combination, a spinning bucket having a removable bottom and an annular cover, means on said cover for holding it in place on said bucket comprising at least one member radially movable to a retracted position entirely within said cover and to a position extending internally of the inner periphery of said cover upon motion of the cover-holding means to bucket-engaging position, means insertable into said bucket for taking hold of said bottom, and an annular sloping surface on said insertable means for engaging and moving said member to retracted position during insertion to release said cover-holding means.

15. In combination, a spinning bucket having a removable bottom and an annular cover, means on said cover for holding it in place on said bucket comprising at least one centrifugally operated bucket-engaging member radially movable to a retracted position entirely within said cover

5 and to a position extending internally of the inner periphery of said cover upon motion of the cover-holding means to bucket-engaging position, means insertable into said bucket for taking hold of said bottom, and an annular sloping surface on said insertable means for engaging and moving said member to retracted position during insertion to release said cover-holding means.

16. In combination, a spinning bucket having 10 a removable cake-supporting element and an annular cover, means on said cover for holding it in place on said bucket comprising at least one member radially movable to a retracted position entirely within said cover and to a position extending internally of the inner periphery of said cover upon motion of the cover-holding means to bucket-engaging position, means insertable into said bucket for taking hold of said element, and an annular sloping surface on said insertable means for engaging and moving said member to retracted position during insertion to release said cover-holding means.

17. In combination, a spinning bucket having 15 a removable bottom and an annular cover, means on said cover for holding it in place on said bucket comprising at least one member radially movable to a retracted position and to a position extending internally of the inner periphery of said cover upon motion of the cover-holding means to operative position, means insertable into said bucket for taking hold of said bottom comprising a cylindrical member terminating in a portion adapted to seat itself firmly upon a cooperating portion of said bottom, said portion constituting a sloped surface adjoining the cylindrical portion of said member whereby insertion of said means into said bucket causes engagement of said sloped surface with said radially movable member and causes motion of said member to retracted position to 20 release said cover-holding means.

18. In combination, a spinning bucket having 25 a removable bottom and an annular cover, means on said cover for holding it in place on said bucket comprising at least one bell-crank lever having one arm arranged for motion into and out of bucket-engagement, means insertable into said bucket for taking hold of said bottom, and means on said insertable means for engaging and moving the other arm of said bell-crank lever to release said cover-holding means.

19. In combination, a spinning bucket having 30 a removable bottom and an annular cover, means on said cover for holding it in place on said bucket comprising at least one bell-crank lever having one of its arms arranged to be moved into and out of bucket engaging position and being eccentrically weighted so that centrifugal force developed upon rotation of the bucket causes motion thereof into bucket-engaging position, means insertable into said bucket for taking hold of said bottom terminating in a portion adapted to seat itself firmly upon a cooperating portion of said bottom, and means on said insertable means for moving said lever to release said cover-holding means.

20. In combination, a spinning bucket having 35 a removable cake-supporting member and a cover, means on said cover for releasably locking said cover to said bucket, a device insertable into said bucket for removing said member, and means on said device for releasing said cover-locking means.

HENRY J. McDERMOTT.
RICHARD W. STANLEY.
